UNITED STATES PATENT OFFICE.

JAMES LIVINGSTONE AND JOSEPH WRIGHT, OF TORONTO, ONTARIO,
CANADA.

HOT-WATER AND STEAM BOILER.

SPECIFICATION forming part of Letters Patent No. 250,087, dated November 29, 1881.

Application filed December 6, 1880. (Model.) Patented in Canada July 29, 1879.

To all whom it may concern:

Be it known that we, JAMES LIVINGSTONE, pattern-maker, and JOSEPH WRIGHT, steam-fitter, both of the city of Toronto, in the county 5 of York, in the Province of Ontario, Canada, have jointly invented certain new and useful Improvements in Self-Feeding Circulating Hot-Water and Steam Boilers; and we do hereby declare that the following is a full, clear, and 10 exact description of the same.

A Canadian patent of applicants for this invention is dated July 29, 1879, No. 10,310, and is extended for a second period of five years, under No. 11,981, from the 29th day of July, 1884, and is further extended for a third period of five years, under No. 11,982, from the 15 29th day of July, 1889.

Our invention relates more particularly to improvements in self-feeding circulating hot-water and steam boilers for heating public houses and private residences; and our improvement consists in certain novelties of construction, hereinafter described and claimed.

In the accompanying drawings, Figures 1 25 and 2 are cross-sections on the lines *a a* and *b b*, respectively, of Fig. 4. Figs. 3 and 4 are plan views on the lines *c c*, *d d*, respectively, of Fig. 1. Fig. 5 is a top view, with portion of cover removed; Fig. 6, a general elevation, with 30 a portion of the outer casing removed; and Fig. 7 is a detail, in vertical section, showing parts of the adjacent sections A^2 and A^3 through one of the ports *J*, which forms the water-communication between these adjacent sections, 35 similar ports, *J*, forming similar connections between the other sections.

A is the boiler, constructed preferably in a cylindrical form, and consisting of a number of independent hollow sections, A' A^2 A^3 A^4 40 A^5 , placed one on top of the other and bolted together at the joints to form a single structure forming the water-boiler.

In the center of the lower section, A' , which is not a water-section, an ash-pit is formed by the upwardly-projecting rib *B*, which rib also supports the grate *C* and grate-ring and defines the size of the fire-chamber *D*.

Between the rib *B* and the outside wall of the lower section, A' , a flue, *E*, is provided to

convey the smoke and products of combustion 50 from the return-flues of the boiler to the smoke-pipe *F*.

The lower section, A' , is provided with a door, *a*, communicating with a passage leading to the ash-pit, and doors *e e*, for cleaning 55 the flue *E*.

The fire-chamber *D* is formed by providing a central opening of sufficient diameter in the next succeeding sections, A^2 A^3 , which sections, together with the sections A^4 A^5 , placed 60 above, are water-sections, and are constructed with a number of flues, *G G'*, through which the smoke and heated products of combustion pass before they escape into the flue *E*, as hereinafter explained.

In the next succeeding sections above the fire-chamber sections the diameter of the central opening is contracted to a sufficient size to form a coal-reservoir, *H*, from which the coal is fed down into the fire-chamber.

The contraction of the central opening in the sections above the fire-chamber causes them to project considerably over the fire-chamber, and affords the opportunity for the construction of flues *G* therein, which convey the smoke and 75 heated products of combustion upward to the chamber *I*. This chamber *I* is formed between the two upper sections, A^4 A^5 , and is provided for the purpose of changing the direction of 80 the heated currents, as indicated by arrows, and connects the uptake-flues *G* with the down-take-flues *G'*, which lead to the lower flue, *E*, and thence to the chimney.

The flues *G* in each section are placed to correspond with each other, and form, when the 85 sections are bolted together, continuous flues, which subdivide the body of water in the sections and expose a large area of heating-surface in addition to the heating-surface exposed to the direct action of the fire. Each of the water-sections is provided with water-ports *J*, the 90 positions of which on the top and bottom sides of each section correspond, in order that the water may circulate upward from the different sections to the hot-water outlets *N N N*, of which three (more or less) may be provided. *K* is the inlet-pipe connecting with the lower water-section, and *N N N* are the outlet-pipes con-

necting with the upper section. At the points where the several water-ports of the different sections come together water and steam tight joints are made with rubber, putty, or in any suitable manner, and the sections are strongly bound together by the bolts a^2 and lugs a^3 . The remainder of the joint between the sections is stopped with putty, fire-clay, or other cement to prevent the escape of the smoke or 10 gases through the same.

The upper section, A^5 , is made concave on its lower face to form the chamber I, and is provided with flues G^3 , corresponding in position to the flues in the lower sections.

15 It will be observed, on examination of the drawings of these water-sections, that the water-spaces are shown by broken horizontal lines, and are marked w , and occupy all the space in these sections, except what is required 20 for the flues. The water-spaces and flues are formed in the process of casting these sections in the foundry, which avoids the expense of putting in wrought-iron tubes, which is generally done in other boilers of this class. We 25 put in wrought-iron tubes, if required.

In connection with chamber I a draft-pipe, M, with damper O is provided, which forms a communication between the aforesaid chamber I and the smoke-pipe F, so that in lighting the fire a direct draft is obtained by opening the damper O, which will be more active from avoiding the descent in the return-flues G' , and which will be found serviceable from time to time in the usual working of the boiler.

30 35 In the practical construction of our boiler we proportion the sections so as to permit of all the water-spaces and flues being properly spaced off, so that they can without difficulty be taken out with a core in the casting of the 40 same in the foundry. When we use wrought-iron shells we put in tubes with an expanding mandrel.

45 Referring especially to the flues G^3 , it will be observed that the products of combustion do not pass through these flues, which products, on reaching the chamber I, are drawn down the return-flues G' to the flue E and thence to the smoke-pipe, by which they are conveyed to the atmosphere. The outlet of these flues G^3 is 50 stopped by the sectional top plate, L, to prevent the upward escape of the smoke therefrom. The plates L are made detachable, in order that a flue-clearer may be inserted into the flues to clean them, when required.

55 60 It will be observed that the upper water-section is made shallower than the remaining sections, and that the outlet-pipes N N N connect with this section. The object of this construction is to reduce and subdivide the body 65 of water immediately before it passes from the boiler, in order that the heat may be applied with the greatest effect. The water is first received into the boiler through the inlet-pipe K in the lowest water-section, and rises from 70 it through the ports J into the next water-section. When this section is full it rises into

the next section through similar water-ports, J, and so on. When heated the water becomes lighter and rises up out of the boiler, passing 75 through the outlet-pipes N. The water being now in the pipes connecting the boiler with the ranges of pipes in the building, it circulates through them, following their curves and bends, and getting colder in passing through these pipes, some of them at a great distance 80 from the boiler. It descends by other pipes joining the pipe K, and again enters the boiler, having made a complete circuit through the building. It is again in the boiler reheated and makes another similar circuit, and so on. 85 The boiler, however, can be used for steam-heating; but it is not necessary to describe the mode of operation for steam, as it would be but a repetition. But little water is used in the hot-water system of heating, because little is wasted, the same water being used over and over again, and when any more is wanted it is fed through the pipe K by pressure or gravitation.

The construction and operation are simple, 90 and ordinary domestics of the household can manage it readily.

Instead of the two rows of flues G and the two rows G' , we may use one row of larger flues in place of G and one row of larger ones in place 95 of G' .

The action of our device may be described thus: Water is supplied by gravitation or otherwise to the boiler, and enters therein through the pipe K in the lowest water-section, A^2 , and on becoming heated loses its density, and rises into the other water-sections, $A^3 A^4 A^5$, through the water-ports J, and, continuing to rise, it leaves the boiler through the pipes N N in uppermost water-section and 100 circulates through the various ranges of pipes in the building, giving out heat through the said pipes and warming the various apartments thereof, and while circulating through these pipes decreases temperature and increases in density, and descends by other ranges of pipes connecting with the inlet-pipe K, by which it re-enters the water-section A^2 , 105 is again heated, rises and circulates, and, warming the apartments of the building, again descends to the boiler, and so on continuously, as required.

We claim as new and desire to secure by Letters Patent—

1. The combination, with the lower water-sections provided with the flues G G', of the top water-section, A^5 , said section being recessed on its under side to form the chamber I, and provided with flues G^3 , as and for the purpose set forth. 120

2. The combination, with a water and steam boiler, A, built up in sections having communicating water-ports J J J, of the inlet-pipe K, and outlet-pipes N N N, arranged and operating substantially as described, and for the 125 purpose set forth.

3. The combination, with the upper section,

A^5 , provided with flues G^3 , corresponding to D, substantially as shown and described, and the flues in the lower sections, of the sectional plate L, substantially as and for the purpose for the purposes set forth.

5 4. In combination with the lower section, A', the second section, A^2 , the third section, A^3 , the fourth section, A^4 , and the top section, A^5 , the coal-reservoir H, and the fire-chamber

D, substantially as shown and described, and for the purposes set forth.

JAMES LIVINGSTONE.
JOSEPH WRIGHT.
